(57) **CLAIM**

The ornamental design for a flat panel display, as shown and described.

DESCRIPTION

FIG. 1 is a perspective view of a flat panel display showing our new design;

FIG. 2 is another perspective view thereof;

FIG. 3 is a front view thereof;

FIG. 4 is a rear view thereof;

FIG. 5 is a right side view thereof, the left side view being a mirror image of the right side view; and,

FIG. 6 is a top view thereof.

The broken lines shown in the drawings are for illustrative purposes only and form no part of the claimed design.

1 Claim, 6 Drawing Sheets

FIG. 2

FIG. 3

FIG. 4

FIG. 5

FIG. 6
